UNITED STATES PATENT OFFICE.

HAROLD W. GOFF, OF NEW YORK, N. Y., ASSIGNOR TO WESTERN ELECTRIC COMPANY, INCORPORATED, OF NEW YORK, N. Y., A CORPORATION OF NEW YORK.

ELECTROMAGNETIC STEP-BY-STEP SWITCH WITH MAGNETIC BRAKE.

Application filed August 7, 1920. Serial No. 402,002.

To all whom it may concern:

Be it known that I, HAROLD W. GOFF, a citizen of the United States, residing at New York, in the county of New York and State of New York, have invented certain new and useful Improvements in Electromagnetic Step-by-Step Switches with Magnetic Brakes, of which the following is a full, clear, concise, and exact description.

10 This invention relates to electromagnetic devices and more particularly to devices of that kind adapted for electrical switching purposes. The specific embodiment of the invention as hereinafter described, comprises 15 a movable contact rotary switch provided with a magnetic brake for stopping the moving element.

In step-by-step switches of the type employing a plurality of stationary contacts and a movable contact brush cooperating therewith, it is essential that a positive means be employed for stopping the movable brush member in order to prevent overthrow, that is, to prevent the movable brush moving past the stationary contact on which it is intended to be stopped at the end of each step.

It necessarily follows that abrupt stopping of the movable member results in noisy operation as well as considerable wear and tear on the switch mechanism and it is accordingly the object of the present invention to provide a stopping means for electromagnetic switches which does not act to abruptly stop the rapidly moving member, but rather to bring it to a more gradual stop thereby reducing the noise and wear to a considerable degree.

20 A feature of this invention resides in the application of a magnetic brake to an electromagnetic step-by-step switch, so arranged as to gradually retard the moving contact member near the end of each step except the last step of any series of steps. A further feature resides in the application of a positive stop which goes into action after the magnetic brake has been applied so that the force of impact between the moving member and the positive stop is very small.

25 One specific embodiment of this invention is illustrated in the accompanying drawing, in which Fig. 1, is a side elevation partially in section, showing a step-by-step switch; Fig. 2, is an elevation of the left-hand end

of Fig. 1; and Fig. 3, is an elevation of the 55 right-hand end of Fig. 1.

On the supporting plate 1, there is shown mounted a semi-circular bank of stationary contacts 2, comprising six rows and cooperating therewith are a set of rotatable 60 brushes 3, which are insulatively mounted and rotatable with shaft 4. Also mounted on plate 1, is an electromagnet 5, having a core 6 of nonmagnetic material which is provided with a longitudinal aperture in which 65 shaft 4 is journaled.

Electromagnet 5 is provided, at its left-hand end, (Fig. 1) with a pole piece 7, which is secured to the core 6. Supporting plate 1 being of magnetic material, forms the 70 opposite pole piece for electromagnet 5. Armature 8 is pivotally mounted on pin 9 which extends between pole piece 7 and plate 1. Pin 9 is made of non-magnetic material. Washers 10, also made of nonmagnetic material, are mounted on pin 9 and serve as 75 separators between the pole pieces and the mounting lugs of the armatures, thereby preventing the magnetic flux from having a continuous path when the armature is in its 80 released position, as shown.

Ratchet wheel 11 is securely mounted on the shaft 4 at the right-hand end of the electromagnet and a stepping pawl 18 attached to the armature is arranged to drive the 85 ratchet wheel 11 together with shaft 4, brushes 3 and stopping ratchet 12. Ratchet wheel 11 is of non-magnetic material and stopping ratchet 12 is of magnetic material.

Stopping pawl 13 carried by armature 8 90 is arranged to swing into engagement with stopping ratchet 12 at the instant the armature reaches its farthest released position, at which time, brushes 3 are properly centered on one of the sets of stationary contacts of 95 the terminal bank 2. On each forward stroke of the armature, pawl 13 swings out of the path of the teeth of ratchet 12 and on the release stroke of the armature, ratchet 12 is rotated sufficiently to move the end of 100 one tooth past the point of pawl 13 before the latter again swings into the path of the teeth.

Contact springs 14 and 15 are arranged to be operated by pawl 18 to make and break 105 the circuit of electromagnet 5. On each downward stroke of armature 8, pawl 18, riding on the back of one of the teeth on

ratchet 11, holds contact springs 14 and 15 together by virtue of its contact with insulator 16 attached to spring 15, until it drops into the recess of the next succeeding tooth, whereupon contact springs 14 and 15 separate thus breaking the circuit of electromagnet 5. Armature 8 is returned to its released position by spring 17 carrying with it pawl 18 and rotating thereby ratchet 11. 10 The relation between ratchet 11 and pawl 18, as will be seen in Fig. 3, is such that as the pawl 18 travels upwardly with the armature, it is moved outwardly toward the contact springs. At a point approaching the 15 end of the release stroke, the contact springs 14 and 15 are forced together thus causing the electromagnet to be energized at that instant whereupon stopping ratchet 12 is moved by magnetic attraction into friction- 20 al engagement with pole piece 7 thereby providing a retarding force which tends to stop further rotation of the shaft and actually slows the shaft down to such a speed that when pawl 13 engages the stopping ratchet 25 12, there is practically no accompanying noise.

On the last step of any series, the current is cut-off so that the magnetic brake cannot act, and pawl 13 abruptly stops ratchet 12. 30 There is therefore, only one stopping click of any consequence emitted for each complete operation of the switch.

In Fig. 3 a diagrammatic representation of an appropriate circuit for this switch is shown. Electromagnet 5 is illustrated therein in dotted lines. For each set of stationary contact terminals in the bank, there is provided a relay 19 with an armature 20 which, when operated, puts ground on its 40 respective terminal completing the circuit for electromagnet 5 when contact springs 14 and 15 are closed.

What is claimed is:

1. In combination, an electromagnetic switch, comprising a bank of stationary contact members, rotatably movable contact members cooperating therewith, an electromagnetic brake operable to retard the rotation of said movable contact members, and 45 a device operable to positively prevent overthrow of said movable contact members when said cooperation with the stationary contact members is effected.

2. In combination, an electromagnetic step-by-step switch, comprising a stationary contact member, a rotary contact member cooperating with said stationary contact member, a shaft for rotating said rotary contact

member, step-by-step means for rotating said shaft, a ratchet wheel on said shaft, a pawl operable to engage and stop said ratchet wheel together with said shaft and rotary contact member at the end of each step and electromagnetic means for frictionally engaging said ratchet wheel prior to the end of each step thereby retarding the motion of said ratchet wheel, shaft and rotary contact member.

3. An electromagnetic step-by-step switch comprising a stationary contact member, an electromagnet, a shaft extending through the core of said electromagnet, a contact brush mounted on said shaft and rotatable therewith, a stepping ratchet wheel on said shaft, an armature for said electromagnet, a stepping pawl for said stepping ratchet operable by said armature, a stopping ratchet on said shaft situated within the magnetic field of said electromagnet adapted upon energization of said electromagnet to frictionally engage a stationary part of said electromagnet, a stopping member operable by said armature to engage said stopping ratchet at the end of each step and prevent overthrow thereof, a source of current for said electromagnet, and means operable to apply said current to said electromagnet prior to the completion of a release movement of said armature.

4. An electromagnetic step-by-step switch, comprising an electromagnet, a core of non-magnetic material for said electromagnet, a supporting plate of magnetic material forming a part of the magnetic circuit of said electromagnet and situated at one end thereof, a pole piece for the other end of said electromagnet, a rotatable shaft of magnetic material extending through said supporting plate, core and pole piece, an armature for said electromagnet; a stepping ratchet mounted on said shaft and rotatable therewith, a stepping pawl carried by said armature, operable to move said stepping ratchet one step upon each release movement of said armature, a stopping ratchet mounted on said shaft in close propinquity to said pole piece and adapted to be drawn into frictional engagement therewith upon energization of said electromagnet, a stationary contact member and a contact brush mounted on said shaft and rotatable therewith, adapted to engage said stationary contact member.

In witness whereof, I hereunto subscribe my name this 28th day of July, A. D., 1920.

HAROLD W. GOFF.
